UNITED STATES PATENT OFFICE.

EDWARD S. JUDKINS, OF EAST PROVIDENCE, RHODE ISLAND.

DESIGN FOR A SHOW-CASE.

SPECIFICATION forming part of Design No. 30,579, dated April 18, 1899.

Application filed March 16, 1899. Serial No. 709,337. Term of patent 7 years.

To all whom it may concern:

Be it known that I, EDWARD S. JUDKINS, of East Providence Center, in the county of Providence and State of Rhode Island, have 5 invented and produced a new and original Design for a Show-Case, of which the following is a specification, reference being had to the accompanying drawings, forming part thereof.

10 Figure 1 is a front view of a show-case, showing my design. Fig. 2 is a vertical cross-section of the same.

The leading feature of my design consists in the projecting molded base, provided with 15 a rope molding and forming the support of the upward-extending glass case.

In the drawings, *a* indicates a glass plate forming the front of the case; *b b*, glass plates forming the ends, and *c* a glass plate forming 20 the top, of the case; *e*, the back of the case. The base, on which the glass case rests, is

formed of the moldings *f*, extending diagonally outward to the rope molding *g*, which extends along the ends and the front and from beneath which the moldings *h* extend inward to a vertical line corresponding with the ends and front of the glass case. The base-board *i* is surmounted with the foliated molding *k*. The corners at the intersection of the sides with the front are rounded. 25 30

Having thus described my invention, what I claim as new, and desire to secure by Letters Patent, is—

The design for a show-case, substantially as herein shown and described. 35

In witness whereof I have hereunto set my hand.

EDWARD S. JUDKINS.
